UNITED STATES PATENT OFFICE.

ABRAHAM COOPER, OF BROOKLYN, NEW YORK.

DESIGN FOR A BRIDGE ARM FOR LIGHTING FIXTURES.

Application filed February 21, 1923. Serial No. 5,237. Term of patent 3½ years.

To all whom it may concern:

Be it known that I, ABRAHAM COOPER, a citizen of the United States, residing in the borough of Brooklyn, in the county of Kings, city and State of New York, have invented a new, original, and ornamental Design for a Bridge Arm for Lighting Fixtures, of which the following is a specification, reference being had to the accompany-

ing drawing, forming part thereof, in which—

Fig. 1 is a side elevation, and

Fig. 2 is a plan showing my new design.

I claim:

The ornamental design for a bridge arm for lighting fixtures, as shown.

ABRAHAM COOPER.
